[57] CLAIM

The ornamental design for a portable fan heater, as
shown.

DESCRIPTION

FIG. 1 is a front-elevational view of a portable fan
heater showing my new design;

FIG. 2 is a side elevation view thereof on a greatly
reduced scale;

FIG. 3 is a bottom plan view thereof on a greatly re-
duced scale; and

FIG. 4 is a rear elevational view thereof on a reduced
scale.

FIG. 1

FIG. 2

FIG. 3

FIG. 4
